SUSPENDERS

Thomas O. Murray, Chicago, Ill.

Application February 28, 1934, Serial No. 713,250

2 Claims. (Cl. 241—7)

My invention relates to suspenders for keeping the trousers of a wearer in normally worn position.

Among the objects of my invention are to provide suspenders which need not pass over and be supported directly by the shoulders of a wearer;

To create suspenders which may be fastened to the vest or coat of a wearer and removably fastened to the trousers;

To provide suspenders which may be unfastened and refastened immediately, so that a user in sitting position does not have to bear the strain and pull of the suspenders;

To supply suspenders which may allow the trousers to be dropped without the removal of coat or vest;

To provide suspenders which will firmly and correctly hold the trousers in normally worn position;

To provide suspenders which will eliminate the nervous strain and wear on clothing of a wearer by eliminating the shoulder straps;

To provide suspenders which are more easily attached for use;

To create suspenders economical of manufacture and durable of wear, and such other objects, advantages and capabilities as will later more fully appear and which are inherently possessed by my invention.

While I have shown herein a preferred embodiment of my invention yet I wish it understood that the same is susceptible of modification and change without departing from the spirit of my invention.

Referring more particularly to the drawing:

Fig. 1 is a front elevational view of my invention, and Fig. 2 is a side elevational view thereof.

Fig. 3 is a perspective view showing my suspenders in actual use. Fig. 4 is a rear elevational view of my invention.

Referring more particularly to the embodiment selected to illustrate my invention I employ a body member 10 of flexible and elastic material. I prefer that the body member be of a single thickness of material, although if desired two or more thicknesses may be used. In order that my suspenders may be adjustable as to length I employ an adjusting means 11 normally and preferably located below the center of the body member. Naturally between the adjusting means 11 and the bottom of the body member 10 my suspenders are of double thickness, and have a front portion 12 and a back portion 13. The 55 crotch 14 of the front and back portions 12 and

13 passes through a slot 15 in combination holding member 16. In the holding member 16 extending below the slot 15 is a rear guide wall 17, at the bottom of which and at right angles thereto is gripping seat 18. At right angles to said gripping seat 18 and continuing upwardly is a front wall 19 preferably cut in the shape of a half circle. Said rear guide wall 17 and front wall 19 run substantially parallel to each other.

The rear guide wall 17 has a cutaway channel 20 leading from the bottom of guide wall 17 upwardly and continuing inwardly into channel 23, which in turn leads inwardly to cut out portion 25. Having exactly the same structure rounded front wall 19 has a corresponding cutaway channel 21 leading upwardly and inwardly from the bottom of rounded front wall 19 into corresponding channel 24 and thence inwardly into corresponding cutaway portion 26.

So that a trouser's loop may enter cutaway channels 20 and 21 and pass through channels 23 and 24 into cutaway portions 25 and 26, the gripping seat 18 has a cutout portion or channel 22 between channel 20 of the guide wall 17 and channel 21 of the rounded front wall 19.

Standing upright between channels 20 and 21 and cut out portions 25 and 26 are anchoring members 27 and 28 which are curved slightly backwardly and away from channels 20 and 21.

At the upper end of body member 10 the elastic or resilient material is folded and held around a metal bar 29 having integral therewith a pin 30 and a clasp 31 for fastening the pin 30 in closed position.

In use my device may be employed as follows:

The wearer will unfasten the clasp 31 and attach the pin 30 at a desired point to the vest or coat 32. He will then adjust the adjusting means 11 to the proper height and, if he has a belt, slip the rear guide wall 17 under the belt 40 and pull the holding member 16 up until the belt rests in the gripping seat 18. If the wearer is not using a belt he may slip a trouser's loop through the channels until it rests within the cutout portion and is held within the corner by 45 the anchoring members 27 and 28.

It will readily be seen that my device may be immediately fastened and unfastened. If the wearer desires, while in sitting position, to remove the strain necessarily caused by the suspenders he may immediately slip off the holding member 16 and thus relieve himself from this unnecessary strain. When the wearer is about to stand all he needs to do is to slip the holding member 16 into normal wearing position and 55

he again has the suspenders in actual supporting use. This feature is a decided advantage because there are many occasions when it is necessary or desirable to remove the suspenders without removing the coat or vest as is now necessary with the prevailing conventional type of suspenders where the same are supported by the shoulders of the wearer.

It is also obvious that with my device there is a considerable saving of wear and tear on the clothing as well as a minimum of pressure on the user.

My suspenders are operated best by employing one on each side of the wearer although if the wearer desires he may add a third suspender at the rear or may place the suspenders at the position best suited to his particular requirements.

Having thus described my invention,

I claim:

- 20 1. Suspenders for the support of trousers without shoulder straps and adapted for wearing over the outer shirt of a wearer, comprising a short body member of elastic or resilient material, a metal bar fastened to the upper end of said body member, said metal bar having integral therewith a pin for passing through and fastening to the inside of the coat or vest of a wearer, a clasp

for fastening the pin in closed position, adjusting means normally located below the center of the body member, said body member being of single thickness above the adjusting means and of double thickness below said adjusting means, and a combined metal holding member attached to the bottom of said body member and having a rear guide wall, a gripping seat and a front wall, said walls and seat each having a channel communicating with a cut out portion, and anchoring members between said channels and said cut out portion for holding a trouser's loop.

2. In suspenders of the class described a combined holding member for gripping either the belt or trouser's loop of the wearer comprising guide 15 and holding means for gripping a belt and means for slipping around and anchoring a trouser's loop, said means having a rear guide wall a gripping seat and a front wall, said seat having an opening and said walls each having corresponding channels and corresponding cutout portions into and through which a trouser's loop may pass, and anchoring members between said channels and cutout portions for positioning said trouser's loop.

THOMAS O. MURRAY.
